ELECTRIC LIGHTING FIXTURE

Stanley McCandless, Hamden, Conn., assignor to
 Century Lighting, Inc., New York, N. Y., a corporation of New York

Application January 19, 1949, Serial No. 71,618

2 Claims. (Cl. 240—52)

1

This invention relates to electric lighting fixtures. More particularly, my invention pertains to electric lighting fixtures of the type used in theatrical, architectural and commercial lighting.

It is an object of my invention to provide an electric lighting fixture of the character described which is constructed to facilitate one-handed relamping, so that the fixture is particularly useful in locations which are accessible only with the aid of very tall ladders.

It is another object of my invention to provide an electric lighting fixture in which a simplified mechanism is employed to move jointly a burner and a louver with respect to a reflector.

It is a further object of my invention to provide an electric lighting fixture of the character described which is rotatable with respect to a support and in which an improved mechanism is included to lock the fixture in any adjusted angular position thereof.

It is an additional object of my invention to provide an electric lighting fixture of the character described which has a rugged compact construction and can be manufactured economically.

Other objects of my invention will in part be obvious and in part will be pointed out hereinafter.

My invention accordingly consists in the features of construction, combinations of elements and arrangements of parts which will be exemplified in the construction hereinafter described and of which the scope of application will be indicated in the appended claims.

In the accompanying drawings in which is shown one of the various possible embodiments of my invention,

Fig. 1 is a front view of an electric lighting fixture constructed in accordance with my invention;

Fig. 2 is a sectional view through said fixture taken substantially along the line 2—2 of Fig. 1;

Fig. 3 is a sectional view taken substantially along the line 3—3 of Fig. 2, and is explanatory of the construction of the burner, the burner focussing adjustment, the pivotal mounting for the louver, and the spring detent for the louver;

Fig. 4 is a sectional view taken substantially along the line 4—4 of Fig. 2, and is explanatory of the construction of the rotary mounting for the housing, the pivotal mounting for the louver, and the fairing for the burner focussing knob;

Fig. 5 is a sectional view taken substantially along the line 5—5 of Fig. 2, and is explanatory of the construction of the burner focussing mechanism;

2

Fig. 6 is a sectional view taken substantially along the line 6—6 of Fig. 2, and is explanatory of the construction of the forward bearing for the burner focussing spindle;

Fig. 7 is a side view of the fixture;

Fig. 8 is an enlarged sectional view taken substantially along the line 8—8 of Fig. 7, and is explanatory of the construction of the lock for the rotary housing mounting; and

Fig. 9 is a sectional view taken substantially along the line 9—9 of Fig. 8.

Referring now in detail to the drawings, the reference numeral 10 denotes an electric lighting fixture embodying my invention and comprising a housing 12 of a standard appearance.

Said housing includes a tubular section 14 having an open forward end and whose rear end is closed by a dome-shaped wall 16 which substantially conforms in contour to the configuration of a specular paraboloid reflector 18 located within the housing and supported from said rear wall. The housing contains a concentrated filament lamp 20. Lamps of this type conventionally are provided either with a spherical envelope as indicated by the full lines in Fig. 2, or with a vertically elongated tubular envelope such as indicated by the dot-and-dash lines in the same figure.

The base of the lamp is received in a socket 22 which is mounted on a support 24, known to the trade as a "burner." Said burner is illustrated herein as constituting a casting comprising several parts. One such part is the socket supporting platform 26. This platform is separated by a step 28 from a narrower platform 30 which acts as a louver support and is disposed at somewhat lower level than the socket platform.

A broad leg 32 depends from beneath the socket platform and a narrower leg 34 parallel thereto depends from beneath the louver platform 30. These two legs are provided with apertures 36, 38 registered along a line parallel to the axis of symmetry of the housing. One of the apertures, for example, the rear aperture 36 is tapped and the other aperture is unthreaded. Said apertures receive a spindle 40 including a threaded portion 42 designed to be screwed into the tapped aperture 36. Thus, when the spindle is rotated, the burner will be shifted parallel to the axis of the spindle, provided that the spindle is held against axial movement.

To fix the axial position of the spindle, I provide an erect plate 44 (Figs. 2 and 6) having a vertically extending slot 46 which rotatably re-

ceives an annular groove 48 in the spindle. The spindle is captively retained in the slot by a swinging gate 50 pivoted at 52 to the plate 44 and designed to be swung down so that its lower edge engages the top of the spindle. The gate is held in this position by a nut and bolt 54 passing through horizontally registered openings in the gate and plate.

Said plate 44 constitutes an upward extension of a horizontal flat sheet metal base wall 56 having laterally and downwardly extending legs 58 which support the wall from the bottom of the housing 12. The bases of the legs 32, 34 are flat and rest on the wall 56, being adapted to slide thereon. To hold the legs against the base wall and maintain the spindle in fixed position with respect thereto, the rear edge of said wall has an upwardly extending tab 58 which is apertured to receive a thin stub 60 extending rearwardly from the back of the spindle. It will be appreciated that as long as the spindle is locked in the plate 44, the stub 60 cannot be disengaged from the tab and therefore the burner 24 will be captively retained in place in the housing. However, simply by opening the gate 50, the burner and its focusing spindle 40 quickly can be removed as a unit for replacement or repair.

Attention is directed to the fact that by having the legs 32, 34 slide on the flat base wall 56, focussing of the beam cast by the paraboloid reflector can be effected with but a single adjusting spindle.

The forward end of the spindle 40 is knurled to fixedly engage a focussing knob 62 which is fabricated from an electric and heat insulating material, such for instance as a synthetic plastic like a urea formaldehyde condensate or cellulose acetate butyrate. The focussing knob is of such diameter that the lower portion of its periphery projects through a slot 64 in the bottom of the housing. Thus, an operator can adjust the focus of the beam emitted from the fixture without danger of burning himself or receiving an electric shock. This is of importance when the fixtures are located at great heights and are accessible only with a high ladder.

The projecting portion of the knob also extends through a slot 66 in a fairing 68 rigidly affixed to the housing around the slot 64. The fairing is formed with a pair of knob-protecting lips 70, one in front of and one in back of the projecting portion of the periphery of the focusing knob, these lips between them defining a groove wherein said portion of the knob lies. With such arrangement, an operator merely needs run his finger across the fairing and his finger automatically will be directed in the proper spot for adjusting the focus. The arrangement is of great assistance where the fixture is located as mentioned above and an operator cannot give his undivided attention to making the focusing adjustment.

In general, a lighting fixture of the type under consideration, i. e., a lighting fixture employing a paraboloid reflector and having a lamp shiftable axially with respect thereto, is intended to throw a comparatively tight or narrow beam, that is to say, a beam constituting a bundle of substantially parallel light rays. In order to prevent the presence of stray or spill rays radiated forwardly directly from the filament and not parallel to the rays of the bundle constituting the tight beam, it is conventional to employ a stray light cut off 72 in front of the lamp 20. This cut off can be of any conventional type, and

by way of example may comprise a plurality of concentric tubular louvers. Another suitable type of stray light cut off is that illustrated which consists of an outer tubular louver 74 within which is disposed a concentric flat baffle 76 supported by radial arms 78 from the louver. For convenience, the elements of the stray light cut off 72 will hereinafter be referred to as "louvers" inasmuch as, regardless of their construction, their function is either that of a louver or its equivalent.

The louvers are supported by a mounting frame 80 constituting a pair of upwardly diverging arms 82, 84 whose tips are permanently secured, e. g., by welding, to opposed portions on the outer surface of the tubular louver 74. The base of the frame 80 is hinged on a pin 86 to a plate 88 fixed, as by a screw 90, to the louver platform 30. The axis of the pin is perpendicular to the axes of symmetry of the reflector and the lamp. With this construction, the frame can be swung away from its operative position, shown in Fig. 2, toward the front of the housing 12 thereby to expedite relamping. Said operative position of the frame is defined by abutment of the base of the frame against the louver platform.

Means also is included to hold the frame in operative position. Said means comprises a spring detent 92 of flat resilient material, firmly secured, as by a screw 94, to the step 28 on the burner. The detent includes a base which rests on the step and a forwardly projecting portion which lies in the path of travel of the base of the frame about the hinge pin 86. Said projecting portion has a rearwardly turned camming tip 96.

It will be appreciated that when it is desired to change the lamp, the louvers can be displaced simply by pulling the same forwardly. However, the spring detent will hold the louvers in position against accidental displacement. Accordingly, single-handed relamping of the fixture is made comparatively simple. Attention is also directed to the fact that by mounting the louvers on the burner they constantly are held in the proper position for correctly cutting off stray light and furthermore they need not be dismounted completely for relamping as is the case with present day fixtures of the same general construction.

The open front of the housing 12 has door frame 98 hinged at 100 to the lower portion of the housing. The part of the door frame diametrically opposed to the hinge is provided with a dog 102 adapted to be caught by a latch 104 designed to retain the door frame in closed position. Said latch comprises a flat spring supported at its rear end in cantilever fashion from the top of the housing and having a toe 106 at its forward end which normally lies in front of the nose of the dog 102. Resting on the shank of the latch is a pin 108 having a tip 110 of reduced diameter which extends through the top wall of the housing. Pressing on the tip releases the latch from the door and permits the door to swing open. It will be observed that the tip 110 is near the top of the door so that an operator simultaneously can press on the pin and hold the door back, thus permitting this operation also to be performed single-handedly.

The housing 12 is supported by a strap iron yoke constituting two pair of vertical depending arms 112, 114. Said arms are rotatably connected to the housing. For example, one arm, e. g., the arm 114, is thus connected to the housing in conventional manner, as by the use of a bolt 116 passing through horizontally regis-

tered openings in the strap 114 and a pivot casting 118 fastened to the interior of the housing, as by rivets. A nut 120 screwed on the tip of the bolt holds the same in place. Optionally the pivot casting may have a central boss extending through an aperture in the housing to simplify the housing mount and in general to improve the appearance of the housing.

The other strap 112 is rotatably secured to the housing in a different manner. Said strap is formed with a non-circular opening 122 into which there is fitted a sleeve 124 of non-circular cross-section negatively matching the cross-section of the opening 122. By way of illustration, the cross-sectional configuration of the sleeve is square, as indicated in Fig. 9. Desirably, the corners of the square are rounded to arcs concentric with the longitudinal axis of the sleeve. The sleeve is rotatably fitted in a horizontal bore 126 formed in a pivot clamping casting 128 which is securely affixed to the housing, e. g., by rivets, at a point diametrically opposed to the pivot casting 118. Like said pivot casting 118, the pivot clamp casting 128 is fashioned with an outwardly extending central boss which protrudes through an opening in the housing and against which the strap 112 rests.

A locking disc 130 rests against the inner surface of the pivot clamp casting, the disc being disposed concentrically about the sleeve 124. Said disc is centrally apertured to a shape negatively matching the configuration of the non-circular sleeve and the sleeve extends through this aperture whereby the disc cannot turn relative to the supporting arm 112. The arm 112, square sleeve 124 and disc 130 are secured to one another by a bolt 132 whose head rests against the outer surface of the strap 112 and whose shank passes through the sleeve, a nut 134 being screwed on the tip of the bolt. By virtue of this arrangement, when the housing is rotated relative to the straps 112, 114, the pivot clamp casting 128 will turn angularly with respect to the locking disc 130 about the axis of the square sleeve 124.

Said pivot clamp casting includes a radial extension 136 which projects beyond the periphery of the locking disc. This extension is fashioned with a through aperture 138 in horizontal register with a matching aperture 140 in the side wall of the housing. Said apertures receive a spindle 140 on whose head a knob 142 is fastened. The spindle is threaded to engage a tapped bore in a locking dog 142' having a portion overlying the peripheral zone of the locking disc 130. Upon tightening the locking dog against the disc the pivot clamp casting 128 will be frictionally locked to said disc in any adjusted angular position of the housing 12 relative to the arms 112. By using a construction such as just described, the locking mechanism, except for its manually manipulative member, is entirely concealed within the housing where it does not detract from the appearance of the fixture, is kept free of dirt and cannot pinch an operator's finger during locking or unlocking or during changing of the angular position of the housing.

All parts located within the housing, except

the reflector and lamp preferably are painted dead black.

It thus will be seen that I have provided an electric lighting fixture which achieves all the objects of my invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, I claim as new and desire to secure by Letters Patent:

1. An electric lighting fixture comprising a housing, a pair of arms disposed on diametrically opposite sides of said housing at a horizontal level, separate means to rotatably connect each 10 of said arms to said housing for turning about aligned horizontal axes, a locking disc within the housing, means to fix one of said arms to said locking disc, a locking dog within and carried by the housing adjacent said locking disc, a knob 20 carried by and disposed externally of the housing, and means connecting said knob and dog for clamping said dog against said disc upon manipulation of said knob.

2. An electric lighting fixture comprising a housing, a pair of arms disposed on diametrically opposite sides of said housing at a horizontal level, means to rotatably connect one of said arms to said housing for turning about a horizontal axis, means to rotatably connect the other arm 30 to said housing for turning about a horizontal axis in alignment with the first horizontal axis, said last-named means comprising a non-circular opening in the arm, a non-circular element in said opening and a circular opening in the housing, said non-circular element extending through said circular opening in a rotatable fit, a locking disc having a non-circular opening negatively matching and receiving the non-circular element, means to secure together said locking disc, 40 said non-circular element and said arm, a locking dog within and carried by the housing adjacent said locking disc, a knob carried by and disposed externally of the housing, and means connecting said knob and dog for clamping said dog against 45 said disc upon manipulation of said knob.

STANLEY McCANDLESS.
